ARTICLE OF FOOTWEAR

Edward P. Bullard III, Fairfield, Conn.

Application May 29, 1950; Serial No. 165,087

7 Claims. (Cl. 36--71)

1

This invention relates to the art of skiing, and particularly to a new and improved device for maintaining the skier's foot in proper position relatively to the ski. This application is a continuation-in-part of application Serial No. 149,997 filed March 16, 1950, in the name of Edward P. Bullard III.

Probably the most essential requirement, insofar as ski equipment is concerned, is that concerning the relation of the ski to the ski boot, and the relation of the ski boot to the foot of the skier.

Ski boots are constructed in a manner to provide a permanent relation with the ski at all times, i. e., the entire bottom of the boot, including the sole and heel is a rigid, non-flexible member that is rigidly fixed to the ski by the usual harness means. The sole is usually much thicker than that of ordinary shoes or boots, and steel plates are usually embedded within the sole and heel in order to insure a continuous non-flexing element that can be rigidly maintained as an integral, non-flexing part of the ski.

The nature of the boot construction, including the steel-reinforced box-like toe construction and the heavy leather uppers, affords little likelihood of maintaining the foot of the skier in the same relation to the ski boot as the latter is related to the ski, although it is just as essential to maintain the sole and heel of the skier's feet in intimate relation with the sole and heel of the ski boots as it is to maintain the boots in rigid relation to the skis.

Heretofore, it has been common practice to lace the ski boot as tightly to the foot as possible in order to effect as nearly as possible this intimate relation of foot to ski boot. Such practice causes concentrated pressures to be applied to various parts of the skier's foot, particularly over the instep, impeding the circulation of blood, causing excessive pain, and requiring frequent loosening of the laces which, of course, are required to be tightened before skiing can be resumed.

The principal object of this invention is to provide a device that will maintain the entire sole and heel of the skier's foot at all times in intimate contact with the non-flexible sole and heel of the ski boot. Other objects include the provision of an inflatable device that will apply any desired force over a relatively large area of the skier's foot above the sole in a manner to maintain the desired intimate contact between the sole and heel of the skier's foot and that of the ski boot; the provision of such a device that can

2

be readily inflated and deflated at the will of the user; the provision of such a device forming an integral part of a sock adapted to be worn with a conventional ski boot; the provision of such a device that is independent of the sock and ski boot; and the provision of a new and improved ski boot embodying as a part thereof such an inflatable device.

The above, as well as other objects and novel features of the improved article of footwear will become apparent from the following specification and accompanying drawings in which:

Fig. 1 is a side elevational view, partly in section, showing the relation of a conventional ski boot with a sock to which the principles of the invention have been applied;

Fig. 1a is a side elevational view of the boot of Fig. 1, but viewed from the opposite side;

Fig. 2 is a sectional elevational view taken substantially along line 2--2 of Fig. 1;

Fig. 3 is a sectional elevational view taken substantially along line 3--3 of Fig. 1;

Fig. 4 discloses a modification comprising an article of footwear worn independently of the sock and embodying the principles of the invention;

Fig. 5 discloses another view of the article shown in Fig. 4;

Fig. 6 is a sectional elevational view through the inflating mechanism of Figs. 4, 5, 7 and 8;

Fig. 7 is a plan view of a new and improved ski boot embodying the principles of the invention and constituting another modification of the invention; and

Fig. 8 is a sectional view taken substantially along line 8--8 of Fig. 7.

Referring to the drawings, and particularly to Figs. 1 to 3 inclusive, the invention is shown as applied to a sock 10 of the usual knitted type commonly employed in skiing. In Fig. 1, the sock 10 is shown on a foot 11 with a conventional ski boot 12. The ski boot 12 includes a rigid, non-flexible sole and heel portion 13 that is maintained in a rigid, non-flexible form usually by the inclusion of metallic plates between the various layers of leather forming the sole and heel 13. The forward portion of the boot 12 includes a box-like toe section 14 that is constructed of relatively heavy-gage sheet metal covered with leather. The remaining upper portion 15 of the boot 12 is constructed of heavy leather so that it will withstand the severe stresses and strains to which the boot is subjected during skiing, and a water-tight joint is provided between a vent 16 and a tongue 17 to prevent the penetration of

moisture into the interior of the boot. Fasteners 18 of usual construction are provided along each edge of the vent 16 to receive the usual lacing thongs.

In an effort to maintain the bottom of the skier's foot in intimate contact with the rigid sole and heel 13 of the ski boot, and because of the thick leather required for the proper maintenance of the boot upper 15, the laces, heretofore, were required to be applied as tightly as possible. Such action produced highly concentrated pressures at various points on the instep of the wearer's foot, resulting in excessive pain and requiring frequent loosening between skiing runs, obviously necessitating re-tightening before beginning a new run.

Referring to Fig. 3, a bladder-like member 19 includes an inner wall 20 attached to the sock 11 by any conventional means such as gluing, stitching, etc., and an outer wall 21 that is vulcanized or heat-sealed to the inner wall along its peripheral edge 22. The bladder 19 may be made of any material capable of maintaining a fluid as air under pressure, such as rubber, heat-sealing plastic and the like. Inasmuch as it is essential to maintain substantially the whole sole and heel of the foot of the wearer in intimate contact with the sole and heel 13 of the ski boot, the bladder 19 must cover a substantial portion of the foot above the sole and heel. In the embodiment of Figs. 1 to 4, the bladder 19 is shown extending from a point just rearwardly of the toes, up over the instep and for a substantial distance on either side of the middle of the instep so that the force required to maintain the sole and heel of the boot and wearer in proper relation is equally distributed over as large an area as is possible. As shown in Fig. 1, the bladder 19 extends rearwardly of the foot 11 to a point adjacent the heel 23, and upwardly above the outer ankle 24. The construction of the bladder in Fig. 1 is such as to leave the outer ankle 24 uncovered while providing an inflatable portion completely surrounding it. The bladder 19 extends over the inner portion of the instep also and includes an inflatable portion 25 that passes upwardly of the inner ankle and down behind the latter in order to provide the greatest possible area of the foot to which the equalized pressure can be applied, thus reducing to a minimum the unit pressure required.

A valve device 26 is integrally attached to the bladder 19 near its upper extremity so as to extend above the top of the boot 12. It may include a housing 27 within which a spring pressed plunger 28 is located, and to which a small hand pump may be removably attached. The valve 26 may be of any convenient design such as the conventional pneumatic tire valve for vehicles, or it may take the form shown in Fig. 6 to be described later.

In practice, with the bladder 19 deflated, the sock 11 is applied to the foot in the usual manner and the boot 12 drawn on and laced only snugly, whereupon the bladder 19 is inflated until the desired pressure is attained to maintain the foot and heel of the wearer in intimate contact with the sole and heel 13 of the boot 12. When it is desired to relieve the pressure on the foot, or to remove the ski boot, it is only necessary to operate the plunger 28 of the valve device 26.

Referring to Figs 4 and 5, a modification of the inflatable article of footwear is shown. In this embodiment, an inflatable bladder 29 in somewhat spat-like form, is similar to that of bladder 19 except that it includes portions covering both

inner and outer ankles, and is provided with a pair of straps 30, 31 to maintain the bladder 29 in proper relation to the foot of the wearer and also in proper relation to the ski boot. A permanently attached valve and inflating device 32 is attached to the upper section of the bladder 29. Referring to Fig. 6, the inflating device 32 includes a body 33 turned from any desirable material, but preferably from a plastic such as nylon or Vinylite, so that it is unaffected by the moisture to which it will be subjected while skiing.

The body 33 is provided with an opening 34 into which is screwed a plug valve 35. A groove 36 is provided part way along the top of the threaded portion of plug valve 35 in such fashion that when the plug 35 is screwed tightly into place, no air escapes through groove 36. However, upon backing the plug 35 outwardly two or more turns, groove 36 is exposed to the atmosphere, thereby venting the body 33. The body 33 is also provided with a float valve 37 that is prevented from falling out of place by a pin 38. A compressible rubber bulb 39 is attached to the top of the body 33 and it includes a float valve 40 similar in action to that of float valve 37. The lower end of body 33 is hermetically sealed to the bladder 29 such that free access is provided from the body 33 to the inside of the bladder 29.

Referring to Figs. 7 and 8, the principles of the invention are shown as applied as an integral part of a new and improved ski boot. In this embodiment of the invention, the ski boot includes a rigid, non-flexible sole and heel member 41, which may be made up of layers of thick leather between which a rigid metallic plate may be located to insure the desired non-flexing characteristic. The upper portion 42 of the new ski boot may be of conventional heavy leather commonly employed in the manufacture of ski boots. Located on each side of the vent 43, and within the interior of the boot, is an inflatable bladder means 44 joined by an inflatable section 45 located just ahead of the instep of the boot. Each of the bladder means 44 extends rearwardly above the ankle, but not entirely surrounding the heel.

Referring to Fig. 8, the bladder members 44 each include outer portions 46 that are cemented or otherwise integrally united to the inner side of the leather forming the upper portion 42 of the ski boot; and, inner portions 47 are provided that are hermetically sealed to the outer peripheral edges of the outer portions 46. A space along the vent 43 is not covered by a portion of the inflatable bladder, but this is necessary in order to facilitate applying the boot to the wearer's foot. Since it is only necessary to fasten the boot snugly to the foot, the common lacing means is dispensed with in the embodiment of Figs. 7 and 8, and fastening means commonly known in the market as a "zipper" 48 is substituted therefor. Of course, any form of fastening means may be employed and the conventional laces are contemplated within the scope of the modification of Figs. 7 and 8. Additionally, the inner surface of the ski boot upper 42 may be provided with pockets made from a relatively thin, soft leather of the general outline of the inflatable members 44, within which inflatable members 44 may removably be positioned. Near the rear of one of the members 44, a connection is permanently made to an inflatable device 49 of the same construction as shown in Fig. 6.

From the foregoing description of Figs. 7 and 8, it is only necessary for the wearer to open the "zipper" 48, apply the ski boot to the foot, close

the "zipper" 48 and operate the inflating means 49, whereupon any desired pressure may be provided over a substantially large area of the wearer's foot necessary to maintain the entire sole and heel of the wearer's foot in intimate contact with the entire sole and heel of the rigid, non-flexing sole and heel 41 of the ski boot. When it is desired to remove the pressure on the foot, it is only necessary to unscrew the plug valve 35 a turn or two, thereby venting the bladder members 44.

Although the various features of the improved article of footwear for use with ski boots and the like have been shown and described in detail to fully disclose several embodiments of the invention, it will be evident that numerous changes may be made in such details, and certain features may be used without others, without departing from the principles of the invention.

What is claimed is:

1. An article of footwear for use with a ski boot and the like having a rigid, non-flexible sole and heel portion, comprising a unitary structure including an inflatable bladder of spat-like form adapted to cover the top of the wearer's foot from a point in advance of the instep, rearwardly over substantial areas of both inside and outside of the instep and to a point adjacent the heel; strap means adapted to hold said bladder on the foot of a wearer; and valve means for facilitating the inflation of said bladder, whereby substantially the entire foot and heel of the wearer is maintained in intimate contact with the rigid, non-flexible sole and heel of the ski boot.

2. An article of footwear for use with a ski boot and the like having a rigid, non-flexible sole and heel portion, comprising a unitary bladder of spat-like form, adapted when worn to cover a substantial area on each side of the center of the instep, and to extend rearwardly to a point adjacent the heel; strap means for holding said bladder on the foot of the wearer; and valve means for facilitating the inflation of said bladder, whereby substantially the entire foot and heel of the wearer is maintained in intimate contact with the rigid, non-flexible sole and heel of the ski boot, said valve means including vent means for facilitating deflation of said bladder.

3. A ski boot accessory comprising a unitary structure including an inflatable bladder of generally spat-like form adapted to be worn with a ski boot of the like, and providing an inflatable pocket extending from one side of the foot continuously across the instep to the other side thereof; strap means for holding said bladder on the foot of the wearer; and means permanently associated with said bladder for inflating and deflating the same.

4. A ski boot accessory comprising a unitary structure including an inflatable bladder of generally spat-like form adapted to be worn with

a ski boot of the like, and providing an inflatable pocket extending from one side of the foot continuously across the instep to the other side thereof; strap means for holding the bladder on the foot of the wearer; and independently operated inflating and venting means permanently associated with said bladder.

5. A ski boot accessory comprising a unitary structure including an inflatable bladder of generally spat-like form adapted to be worn with a ski boot or the like, and providing an inflatable pocket extending from one side of the foot continuously across the instep to the other side thereof; strap means for holding said bladder on the foot of the wearer; a valve body permanently fixed to said bladder; a manually operable valve and floating valve in said valve body and an inflating bulb fixed to said valve body.

6. An article of footwear for use with a ski boot or the like comprising in combination, a unitary structure including an inflatable bladder adapted when worn to cover substantially the entire area of the foot as viewed in plan from the front of the instep to behind the ankle; sole straps adapted to hold said bladder in fixed position relatively to the foot; and a three-way valve means fixed to said bladder at its rearward extremity for facilitating its inflation and deflation.

7. As an article of footwear for use with a ski boot or the like having a rigid, non-flexible sole and heel portion and an upper portion of relatively heavy leather, a unitary structure including an inflatable bladder-like member adapted when worn to cover a substantial portion of the instep of the wearer; resilient strap means adapted to maintain the bladder in fixed position relatively to the foot of the wearer; and a multi-way valve means integral with said bladder at its rearward extremity on the outside of the wearer's foot for facilitating inflation and deflation of said bladder member.
